UNITED STATES PATENT OFFICE.

CHARLES O. HEGGEM, OF MASSILLON, OHIO, ASSIGNOR TO THE RUSSELL & CO., OF SAME PLACE.

TRACTION-ENGINE.

SPECIFICATION forming part of Letters Patent No. 529,490, dated November 20, 1894.

Application filed June 18, 1894. Serial No. 514,859. (No model.)

To all whom it may concern:

Be it known that I, CHARLES O. HEGGEM, a citizen of the United States, and a resident of Massillon, county of Stark, State of Ohio, have invented a new and useful Improvement 5 in Traction-Engines, of which the following is a full, clear, and exact description, reference being had to the accompanying drawings, making part of this specification.

10 My invention relates to improvements in traction engines, the objects of which are to provide means to more perfectly utilize the steam power, and thereby save a large quantity of fuel; to provide a spring foot board, for 15 the comfort of the engineer, and a conveniently disposed water-tank.

With these objects in view, my invention relates to certain features of construction and combination of parts as will be hereinafter 20 described and claimed.

Figure 1 is a perspective view illustrating my invention; Fig. 2, a similar view showing the rear end of the boiler or fire box and the spring foot board secured thereto. Fig. 3 is a 25 similar view of a fragment of the foot board and supporting frame. Fig. 4 is a plan of foot board supporting frame; Fig. 5, a section showing the spring under the foot board and resting on the supporting frame.

30 C represents the boiler, which may be of any of the well known and approved tubular forms, on which is mounted an engine frame D, having therein slides a, for the cross-head b. To the end of the frame D is secured the 35 smaller or high pressure steam cylinder E, supported on a bracket F, secured to the side of the boiler. A bracket as G, similar to bracket F, is secured to the smoke-box, H, at the front end of the boiler. On this bracket

40 G is secured the second or larger steam cylinder, J, which is also secured to the cylinder E, by the arm c. Steam is admitted through the pipe d, connecting the boiler with the steam chest, the flow of which is regulated by the

45 governor e. The steam having exerted its energy to move the piston in the cylinder E, is exhausted into the pipe f, connecting the exhaust with the steam chest of cylinder J, and after exerting its energy on the piston head in cylinder J, which is secured on the same piston rod L, to which the head in cylinder E

is secured, it is exhausted through the exhaust pipe M, into the smoke stack N.

The steam chests and slide valves inclosed therein are on the reverse side of the cylinders, and consequently not shown, and may be of any of the well known and approved forms, and are actuated by an eccentric on the engine shaft O, in the usual way. In the construction of a compound tandem engine 55 for traction engines, the necessary location of the gear wheels, in front of the drive wheels B, makes it absolutely necessary that the second steam cylinder be supported in front of the boiler. 65

The piston rod L, and cross-head b, are connected with the crank wheel P, by the connecting rod Q, through which the steam power is transmitted to the shaft O, having a gear connection with the drive wheels B, by which 70 the machine is driven over the ground.

To the bracket F is secured the pump barrel R. The head of the pump with the valves therein is located at the side and between the cylinders E and J. The pump plunger g is 75 connected to an arm h, secured to the cross-head b.

I do not regard it necessary for me to enter upon any extended statement of the advantage of the compound cylinders or second use 80 of steam on traction engines.

Below the boiler and secured thereto, is provided a water tank S, adapted to carry a considerable supply of water, which is passed into the tank through the aperture k. When 85 pumping water from the tank to the boiler, a rubber hose is connected with the pump pipe l, and dropped into the tank through the funnel aperture k.

At the rear end of the boiler, or rather on 90 the rear plate of the fire box, are secured hinge plates T, having at their upper ends lugs m, and at their lower ends, sockets as n. To the lugs m is hinged the frame U, which serves as a support for the foot board V. In the 95 frame U are provided sockets as o, in which are placed coiled springs p, as shown in Fig. 5, one end to rest in the socket o, the other in a cup q, secured to the under side of the foot board as shown in Fig. 5. In the socket n, 100 on hinge plate T, is also provided a coiled spring r, as shown in Fig. 3.

At the rear portion of the frame U, are provided trunnions s, to which the foot board U is hinged as shown in Fig. 3. The front ends or toe portions of the frame U are adapted to 5 pass between the lugs m on the hinge piece T, and having perforations to register with the perforations in the lugs m, are pivotally secured therein by the pins t.

In the heel portion of the frame U, is provided a socket v that passes over the spring r, and socket n, when the frame is in operative position as shown in Fig. 2.

To give better access to the lower door of the fire box, the frame and foot board may be 15 turned up on its hinges, or removed by taking out the pins t. The object sought by this feature of my invention is to provide an easy riding and removable foot board for the engineer.

20 Having thus fully described the nature and object of my invention, what I claim is—

1. In a compound traction engine, the combination with the boiler, the bracket secured thereto, the cinder box and bracket, said 25 brackets being located above the front supporting wheels, the cylinders secured to said brackets and located respectively in front and in rear of the smoke stack, and the bars connecting said cylinders together, of the 30 pump secured to the rear bracket, the water tank secured to the under side of the boiler intermediate the front and rear wheels, the pipe connecting said pump and tank, the piston rod and cross head, the arm secured to the

cross head and the pump rod connected therewith, substantially as described. 35

2. In a traction engine, the combination with the plates secured to the front of the boiler and provided with lugs, of the frame removably pivoted thereto, the foot board 40 pivoted at its front end to the frame, the sockets formed in said frame, the sockets secured to the foot board and the coiled springs, substantially as described.

3. In a traction engine, the combination 45 with the plates secured to the front of the boiler and provided with lugs, of the frame removably pivoted to said lugs, the foot board pivoted or hinged at its outer end to said frame, the sockets formed in said frame, the 50 sockets secured to the lower ends of said plates and the coiled springs located therein, substantially as described.

4. The combination with a steam boiler for traction engine, of a foot board comprising 55 the hinge pieces T, having lugs m, socket n, foot board frame U, pivotally secured to the hinge piece T, and having sockets o and v, and trunnions s, foot board V, hinged thereto, and the springs p and r, substantially as de- 60 scribed and for the purpose set forth.

In testimony whereof I have hereunto set my hand this 28th day of May, A. D. 1894.

CHARLES O. HEGGEM.
